UNITED STATES PATENT OFFICE.

LE ROY C. TRYON, OF MARSEILLES, ASSIGNOR OF ONE-HALF TO CLARENCE E. TRYON, OF OTTAWA, ILLINOIS.

GRAIN-WEIGHING APPARATUS.

SPECIFICATION forming part of Letters Patent No. 398,473, dated February 26, 1889.

Application filed September 5, 1888. Serial No. 284,664. (No model.)

To all whom it may concern:

Be it known that I, LE ROY C. TRYON, a citizen of the United States of America, residing at Marseilles, in the county of LaSalle 5 and State of Illinois, have invented certain new and useful Improvements in a Grain Weighing and Registering Apparatus, of which the following is a specification, reference being had therein to the accompanying drawings, and the letters and figures of reference thereon, forming a part of this specification, in which—

Figure 1 is a perspective view of the grain-weigher as it would appear ready for use and 15 connected with the discharge-elevator of a separator. Fig. 2 is a perspective view of the oscillating chute for alternately conducting grain to the buckets and of the mechanism for oscillating said chute, and of the lower end 20 of the grain-spout leading from the elevator of a separator to the buckets connecting with said chute. Fig. 3 is a face view of one of the journal-boxes of the tilting buckets and for securing the frame together that supports the 25 buckets, and Fig. 4 is a perspective view of one of the spring-latches for engaging the inner end of a scale-beam.

Referring to the drawings, B is a rectangular frame having a bail, F, located across its 30 central part for suspending the device, said frame bearing a shaft journaled in the boxes E and arranged parallel with said bail across said frame.

T are two similar and equal oscillating 35 grain-measuring buckets triangular in form in cross-section, and connected with each other so their mouths are at right angles with each other, and secured to shaft S, passing between them, by means of the radial arms W and W, 40 boxed to said shaft. The arms W W, secured to the sides of said buckets, are each provided near their outer ends with a spring-latch, Z, for respectively and alternately engaging the inner ends of the scale-beams D D, fulcrumed 45 in posts P P, secured to frame B, and having, respectively, the sliding weights G G. The upper ends of said posts are formed to extend over said scale-beams to prevent their scaled ends from dropping down too far when the 50 scale-beams are released from said latches. Springs *tt*, placed behind said latches, between

them and the extending arms O of said arms W, hold said latches forward to their work. These latches are provided with a laterally-extending tail-piece, V, for extending under 55 the arm W to prevent the springs from moving the latches too far forward. The rear ends of the arms W terminate in the extension O' for engaging the under side of frame B, and prevent the buckets from oscillating too far 60 upward.

R is a cranked rock-shaft arranged above and parallel with shaft S and journaled in bail F, and supporting in its cranked portion the oscillating chute K. Said shaft R has a 65 crank, *a*, on one end, which is connected with a crank-lug, *n*, of the shaft S by means of link C, through the medium of which connection the oscillation of shaft S rocks shaft R and chute K in the opposite direction from the 70 buckets, so as to cause grain to be conducted alternately to the buckets.

L is a grain-spout secured at its upper end to the discharge end of a separator-elevator A by means of a swivel-bolt, J, so said spout may 75 swing laterally.

H is a brace having its upper end pivoted to the said spout near its outer end for supporting it, and having its lower end formed to enter loosely one of a vertically-arranged series of holes in the bar H', designed to be secured to the side of a separator, so said brace may move laterally at its outer end with said spout, and so its lower end can be vertically adjusted in said holes to elevate or lower the 85 outer end of said spout.

The frame B, with its buckets T, is suspended on the outer end of the spout L through the medium of bail F in triangular-shaped notches cut in the two sides of the said spout 90 in such manner that it will alternately discharge grain in said buckets through the medium of the oscillating chute K. The sides of said spout extend beyond its bottom, so that when the chute K is oscillated, as 95 shown in Fig. 1, it forms an extension of the bottom of the spout L to conduct the grain to the bucket farthest from the elevator, and when the said chute is oscillated to the reverse position, as shown in Fig. 2, so as not to 100 form a continuation of the floor of spout L, said spout will discharge in the opposite

bucket, and the chute will then arrest the grain as it leaves the spout and assist in directing it to said opposite bucket.

5 *d* is an apron arranged across the spout *L*, near its discharge end, for arresting the velocity of the grain, so it will not strike the chute and buckets with too great force and be scattered and lost.

10 If desired, the buckets or chute may be connected with a tally or registering device for keeping tally of the quantity of grain passing through the buckets.

15 In operation the device is designed to be used with a grain-separator, or any other place where it is necessary to weigh and keep tally of grain; but in this instance it is shown in use with a separator and suspended from its grain-discharge spout in such manner that the spout and its appendages may be moved laterally to deposit the weighed grain in any receptacle desired. It is intended to set the weights *G* along on the scale-beams at any point desired to indicate the number of pounds a bucket should hold. When the required 20 quantity of grain has entered a bucket, the weight of the grain will overcome the scale-beam and cause the buckets to oscillate and change positions and discharge the filled bucket, and simultaneously oscillate the chute 25 *K* and cause the opposite bucket to be filled, so that the grain automatically oscillates the buckets to alternately be filled and discharge the required quantity of grain indicated by 30 the scale-beams.

Having thus described my invention, what I 35 claim as new, and desire to secure by Letters Patent, is as follows, to wit:

1. The combination of the frame *B*, having the scale-beams *D D*, the oscillating buckets *T T*, having, respectively, the latches *Z Z*, and 40 the oscillating chute *K*, connected with said buckets in such manner as to be oscillated thereby simultaneously in a reverse direction, substantially as and for the purpose set forth.

2. In a grain-measuring device, the combination of the oscillating chute, the similar and equal oscillating measuring-buckets, the scale-beams and the mechanism for detachably connecting said buckets therewith, and the mechanism, substantially as described, whereby the 45 chute and buckets are oscillated simultaneously and in reverse directions from each other, substantially as and for the purpose set forth.

3. The combination of the frame *B*, having the bail *F*, the scale-beams *D D*, spring-latches *Z Z*, shaft *S*, having the crank-lug *n*, cranked shaft *R*, having the crank *a*, link *c*, connecting said crank and crank-lug, oscillating chute *K*, spout *L*, having its floor at its lower end 50 shorter than its sides, brace *H*, and the mechanism, substantially as described, for adjustably connecting said spout with a separator, substantially as and for the purpose set forth.

LE ROY C. TRYON.
